Inventor

William M. Brunst

By James, James, his Attorney s,

UNITED STATES PATENT OFFICE.

WILLIAM M. BRUNST, OF COLUMBUS, OHIO, ASSIGNOR TO THE KINNEAR MANUFACTURING COMPANY, OF COLUMBUS, OHIO, A CORPORATION OF OHIO.

ELEVATOR-DOOR.

1,354,596.

Specification of Letters Patent.

Patented Oct. 5, 1920.

Application filed November 24, 1919. Serial No. 340,265.

To all whom it may concern:

Be it known that I, WILLIAM M. BRUNST, a citizen of the United States, residing at Columbus, in the county of Franklin and State of Ohio, have invented a certain new and useful Improvement in Elevator-Doors, of which the following is a specification.

This invention relates to the type of elevator door that is designed to be raised to project above the top of the doorway and pass the sill of the next doorway above, the aim of the invention being to provide an improved construction of this type of door and means for operating and latching the same. Other objects will appear from the detailed description herein.

The invention is embodied in the example herein shown and described, the features of novelty being finally claimed.

20 In the accompanying drawings—

Figure 1 is mainly a view in elevation with parts in section looking toward the doorway side of the elevator shaft.

Fig. 2 is a vertical section on the line 25 II—II Fig. 1, looking to the right and showing the door down or in closed position.

Fig. 3 is a similar section showing the door partially raised.

30 In the views 5, 5, designate the floors of the building and 6 the wall of the building through which the doorways leading to the shaft or well are formed. The tops of said doorways are indicated by broken line 35 in Figs. 2 and 3 and the lower portion of a doorway is indicated at 7 Fig. 1. The sills of the doorway are indicated at 8. Hinged at 9 at each side of the lower portion of the doorway are channels 10 having their 40 open sides facing each other and being of a length to extend upward beyond the line of the top of the doorway.

Each doorway is to be provided with a door like that designated 11 and the same 45 may be counterweighted as by weights 12 hung on chains 12^a connected with rods 13 projecting from the upper ends of the door and passing over pulleys 14 suitably journaled in the well to facilitate the operation 50 of the door. The door 11 is of a width to fit and slide in the channels 10 and said door is capable of oscillation toward and from the doorway with the channels on the hinging points 9.

Secured on the wall 6 and flanking the 55 upper end of the doorway is a bracket 17 having a cam slot 18 into which extends the rod 13 so that when the door is raised it is deflected at its upper portion by said slot. Also secured on the wall 6 and flanking the upper end of the doorway is a bracket 19 containing fixed therein a short channel piece 22. Said bracket is also furnished with a stop 22^a adapted to limit the deflection of the door (caused by the cam 60 slot) to a position where the hinged channels 10 align with the short channel pieces 22. Hence when the door is raised it continues its upward movement through said channels 22. The short channel pieces 22 65 serve as guides to keep the door in a definite position during the movement after it enters said pieces. The cam slots are open at their upper ends and the said channel pieces guide the rods 13 into said slots when the door is 70 lowered toward closing position. The rods 13 can be provided with suitable anti-friction devices where they engage the cam slots.

The car or carriage designated 43 is 80 equipped with a vertically arranged endless belt or chain 23 traveling over wheels 24 and 24^a journaled in the top and bottom of the car, said belt being provided with a cross pin 23^a.

85 Secured to the lower corners of the door are brackets 15 containing suitable bearings to receive a rock shaft 16. Mounted on the brackets 15 is a gravity latch 40 carrying and guided by a sliding stem or pin 41 90 working in a perforated boss 42. On the building near the door sill in vertical line with the path of the pin 41 is a two-part stop 30 against the upper part of which the pin 41 abuts when the door is lowered to nearly 95 closing position, said abutment causing a cessation of downward movement of the pin and the latch 40.

The rock shaft has secured to each of its ends a latching device comprising a pair of parallel wings each having hooks or lugs 25, 26, 27 and 28. The hook 25 engages the lower side of the stop 30 on the wall of the well and latches the door in closed position as shown in Fig. 2. The hook 27 is engaged by the pin 23^a on the endless belt 23 when the latter member is operated to raise the door as shown in Fig. 3. When the latching

device is raised the hook 28 thereof is thrown under the gravity latch 40 and locked in that position so that when the door is to be closed by reversing movement 5 of the belt 23 and its pin 23^a, the latter engages the hook or projection 26 to force the door downward. When, however, in the downward movement of the door the pin 41 10 abuts against the upper part of the stop 30, the gravity latch is held from further movement thereby permitting the escape of the hook 28 and the reengagement of the hook 25 with the lower part of the stop 30 to latch the door as before indicated and 15 as shown in Fig. 1.

The car can, of course, pass a door without stopping at a floor or a door may be passed without operating it, such operation taking place only when the operating 20 mechanism provided for that purpose is actuated, such mechanism in the instance shown being the belt or belts 23 and the pins thereon. The latch and door actuating devices where shown in pairs are so provided 25 to secure a balance in contact and strains.

With this construction it will be observed that the door can be of full height to permit the movement of passengers and freight into and out of the car and also that the door 30 can be raised into the well to project somewhat above the top of the car.

The forms of the parts can be changed without departing from the gist of the invention as claimed.

35 What I claim is:

1. The combination with a building having an elevator shaft, and a doorway leading from the floor of the building to the shaft, and a car to move in said shaft, of an upwardly sliding door for said doorway, and a guide and support for said door hinged to the shaft wall.

40 2. The combination with a building having an elevator shaft, and a doorway leading from the floor of the building to the shaft, and a car to move in said shaft, of an upwardly sliding door for said doorway and guides for the door hinged to the shaft wall near the lower corners of the doorway.

45 3. The combination with a building having an elevator shaft, and a doorway leading from the floor of the building to the shaft, and a car to move in said shaft, of an upwardly sliding door for said doorway, a guide and support for said door hinged to the shaft wall, and means for causing the deflection of the door and guide when the door is raised.

60 4. The combination with a building having an elevator shaft, and a doorway leading from the floor of the building to the shaft, and a car to move in said shaft, of an upwardly sliding door for said doorway, and guides for the door hinged to the shaft wall 65 near the lower corners of the doorway and

means for deflecting the door and guides when the door is raised, said means consisting of a pin on the door and a bracket in the shaft having a cam slot engaged by said pin.

70

5. The combination with a building having an elevator shaft, a doorway leading from the floor of the building to the shaft, and a car to move in said shaft, of an upwardly sliding door for said doorway, a 75 guide and support for said door hinged to the shaft wall, means for causing the deflection of the door and said guide, and a second but stationary guide for the door with which the first named guide is alined when the 80 door is deflected.

6. The combination with the door of an elevator shaft that is raised and lowered and a car in said shaft, of means for latching and raising the door comprising a rocking member carried by the door, said rocking member having a latching projection to engage the shaft to hold the door closed and means on the car to engage said rocking member to release the latching projection 90 and raise the door.

85

7. The combination with the door of an elevator shaft that is raised and lowered and a car in said shaft, of means for latching and raising the door comprising a rocking member carried by the door, said rocking member having a latching projection to engage the shaft to hold the door closed, means 95 on the door to hold said latching projection disengaged, and means on the car to engage said rocking member to raise the door.

100

8. The combination with the door of an elevator shaft that is raised and lowered and a car in said shaft, of means for latching and raising the door comprising a rocking member carried by the door, said rocking member having a latching projection to engage the shaft to hold the door closed, means on the door to hold said latching projection disengaged, means on the car to engage said rocking member to raise the door and means to automatically release said rocking member when the door is about to close.

105

9. The combination with the door of an elevator shaft that may be raised and lowered and a car in said shaft, of means for latching and raising and lowering the door comprising a rocking member carried by the door, said rocking member having a latching projection to engage the shaft to hold the door closed, means for latching said rocking member with said projection disengaged from the shaft, means on the door for automatically releasing said last named latching means when the door is about to close and means on the car for engaging said rocking member to raise and lower the door.

110

10. The combination with the door of an elevator shaft that may be raised and lowered and a car in said shaft, of means for 115

120

125

130

latching and raising and lowering the door comprising a rocking member carried by the door, said rocking member having a latching projection to engage the shaft to hold the door closed, means for latching said rocking member with said projection disengaged from the shaft, means on the door for automatically releasing said last named

latching means when the door is about to close and means on the car for engaging 10 said rocking member to raise and lower the door, said last named means adapted to move the rocking member into its latched position when disengaged from the shaft.

WILLIAM M. BRUNST.
